(57) **CLAIM**

The ornamental design for a patient monitor and holder, as shown and described.

DESCRIPTION

FIG. 1 is a perspective view of a patient monitor and holder embodying our new design;

FIG. 2 is another perspective view thereof;

FIG. 3 is top view thereof;

FIG. 4 is bottom view thereof;

FIG. 5 is a side view thereof;

FIG. 6 is another side view thereof;

FIG. 7 is a front view thereof;

FIG. 8 is a back view thereof;

FIG. 9 is another perspective view thereof in an example condition of use;

FIG. 10 is a perspective exploded view thereof;

FIG. 11 is another perspective exploded view thereof;

FIG. 12 is top exploded view thereof;

FIG. 13 is bottom exploded view thereof;

FIG. 14 is a side exploded view thereof;

FIG. 15 is another side exploded view thereof;

FIG. 16 is a front exploded view thereof;

FIG. 17 is a back exploded view thereof; and,

FIG. 18 is another perspective exploded view thereof in an example condition of use.

Broken lines, where shown, are used to illustrate portions of the patient monitor and holder or environmental subject matter that form no part of the claimed design.

1 Claim, 12 Drawing Sheets

Related U.S. Application Data

continuation of application No. 29/775,403, filed on Mar. 23, 2021, now Pat. No. Des. 933,234, which is a continuation of application No. 29/702,162, filed on Aug. 16, 2019, now Pat. No. Des. 917,704.

(58) Field of Classification Search

CPC A61B 5/00; A61B 5/021; A61B 5/02141; A61B 5/02158
